LOCOMOTIVE STOKER

Charles J. Surdy, Tuckahoe, N. Y., assignor, by
mesne assignments, to The Standard Stoker
Company, Incorporated, a corporation of Dela-
ware

Original application July 20, 1935, Serial No.
32,339. Divided and this application January
29, 1937, Serial No. 122,919

2 Claims. (Cl. 198—15)

In locomotive stokers of the type to which this invention has reference, the main conveyor member extends from beneath the tender fuel bin to a point beneath the locomotive cab deck and is so arranged that the forward end of such main conveyor is at a substantial elevation above the portion of said conveyor rearward of its forward end. The forward end of the main conveyor member is connected by a flexible joint to the rearward end of a fuel elevating conveyor which is rigidly secured to the hollow backwall of the locomotive firebox. Thus, the main conveyor member is, in effect, suspended from the elevating conveyor on the locomotive.

15 This construction imposes a considerable strain upon the flexible connection between the two conveyors, and these strains are transmitted to the hollow backwall of the locomotive firebox upon which the elevating conveyor is supported, resulting in a weakened boiler structure.

Therefore, it is the principal object of this invention to relieve this strain upon the flexible joint between the two conveyors and the boiler backwall by providing an additional support for 25 the main conveyor member, such additional support being carried by the frame of the locomotive in such a manner so as not to transmit any strains to the boiler backwall.

A still further object of my invention is the provision of means intermediate the ends of said transfer conveyor member for additionally supporting the latter during its vertical, transverse and longitudinal movement with reference to the locomotive and tender.

35 Other objects and advantages of this invention consist in the novel relation of parts which will become apparent as the following description is read in connection with the accompanying drawing, wherein,

40 Fig. 1 is a central vertical medial section of adjacent ends of a locomotive and tender with the invention embodied therein and shown in similar section; and

45 Fig. 2 is a fragmentary view illustrating one modification of the invention shown in Fig. 1.

Referring first to Fig. 1, the locomotive A includes a boiler 10 provided with a hollow backwall 11 at the rear of the firebox 12. In the backwall 11 is the firing opening 13 which is above the level of the cab deck 14 and the grates 15. Coupled to the locomotive at C is a tender B having a fuel bin 16 above the apertured floor 17.

The improved stoker for transferring fuel from the bin 16 to the firebox 12 is indicated generally at S and it includes the transfer con-

veyor member 18 having a trough portion 19 movably mounted by means of the rollers 20 beneath the fuel bin 16 to receive fuel therefrom. Within the trough portion 19 is a conveyor screw 21 driven from its rearward end by gearing 22 and extending forward of the tender. Immediately forward of the conveyor screw 21, the transfer conveyor member 18 is provided with a forwardly inclined tubular portion 23 having its lower wall 24 stepped downwardly at its rearward end and thence extending upwardly and forwardly to the locomotive.

Within the forwardly inclined tubular portion 23 is a conveyor screw 25, the rearmost fuel impelling flight 26 of which is spaced forward from 15 the delivery end of the conveyor screw 21 and also offset axially therefrom in a downward direction. Between the trough portion 19 and the tubular portion 23, the transfer conveyor member is provided with a bearing 27 within which is 20 journaled a shaft 28 provided at its forward and rearward ends with universal joints 29 and 30, respectively. The joint 29 connects the conveyor screw 25 in operative relation and is so disposed that it is not within the passage for 25 fuel between the conveyor screws 21 and 25, thereby eliminating any fuel degradation at this point. The universal joint 30 operatively connects a shaft 31, driven by the gearing 22, with the journaled shaft 28 for transmitting power to 30 operate the conveyor screw 25.

At its upper forward end, the tubular portion 23 is provided with a spherical shell 32 which is received in a complementary seat 33 of the riser member 34. The latter is rigidly supported from 35 the boiler backwall 11 by a bracket 35 and is inclined forwardly from the seat 33 at a greater angle of inclination than the tubular portion 23 and greater than 45 degrees. Within the riser member 34 is a conveyor screw 36, at its rear- 40 ward end universally jointed as at 37 to the conveyor screw 25, and terminating at its upper end adjacent the mouth 38 of the riser member. Fuel distributing means 39 disposed at the firing opening 13 serves to distribute over the grates 45 the fuel discharged through the mouth 38 of the riser member 34. The tubular portion 23 is provided with a foot pad 40 having a spherical bottom which rests upon a spherical surface 41 of the bracket 42 supported on the locomotive 50 frame 9, thereby forming an additional support for the transfer conveyor member intermediate the ends thereof.

The support bracket may be better described as being saucer or dish shaped in which is seated 55

the bottom of the foot pad 40 much after the fashion of a cup resting in its saucer, whereby contact is maintained between the adjacent surfaces of the pad and bracket. This forms an additional support for the transfer conveyor member during its free swinging movement on the locomotive and tender, and also relieves the strain from the universal connection between the adjacent ends of the tubular portion 23 and the riser member 34.

It will be apparent from the drawing that, since the spherical shell 33 is at a considerable elevation above the main portion of the transfer conveyor 18, said conveyor is, in effect, suspended from the riser member 34. This imposes a strain upon the universal connection 32, 33 which is in turn transmitted to the backwall 11 by reason of the fact that said backwall rigidly supports the conduit member 34. Therefore, it is clear that the provision of an additional support on the locomotive frame 9 effectively relieves this strain.

Fig. 2 illustrates a modification wherein the tubular portion 50 of the transfer conveyor member 18 is inclined at the angle of inclination of the riser member 51, which is at an angle greater than 45 degrees, and in alignment therewith. Within the tubular portion 50 is an elevating screw 52, the lower end of which is operatively connected to gearing 53 driven by a shaft 54 which leads forwardly from the gear drive at the rear of the screw 21. The gearing 53 is housed in a casing 55 carried by the transfer conveyor member 18. At its upper end, the screw 52 terminates within the riser member 51 at a point below the level of the distributing means 39. The advantage of this construction over that of Fig. 1 is that the screw 52 is inclined at a relatively steep angle, and of itself urges fuel through the riser member by the direct action of its flights.

Since the tubular portion 50 is in alignment with the riser member 51, the spherical seat 51a of the latter affords considerably less support for the ball member 60 of the tubular portion 50 than does the universal joint construction illustrated in Fig. 1. Furthermore, the conveyor 18 also carries the additional gearing 53 for the screw 52, so it will be obvious that the use of the additional supporting means, comprising the bracket 42 carried by the locomotive frame 9 and the pad 40 which is formed with tubular portion 50, is of special advantage in this modification in relieving the strains imposed by the conveyor 18 upon the backwall 11.

This application is a division of my co-pending application Serial No. 32,339, filed July 20, 1935, for improvements in Locomotive stokers, patented Mar. 16, 1937, No. 2,027,304.

The following is claimed as new and useful:

1. In combination with an intercoupled locomotive and tender, the former having a boiler backwall and a frame, and the latter being provided with a fuel bin, a fuel transfer conveyor leading forwardly from said tender to said locomotive comprising a trough portion underlying said bin and a conduit portion rigid with said trough portion, the forward end of said conduit portion being disposed above the level of said trough portion, means carried by said trough portion movably supporting said transfer conveyor on the tender, means carried by the boiler backwall arranged to flexibly support the forward end of said conduit portion, said fuel transfer conveyor being provided with a depending foot member, and a support member carried solely by the frame of the locomotive, one of said members at its free end having a concave surface and the other of said members at its free end having a convex surface, one of said curved surfaces fitting into the other of said curved surfaces, the engagement of said curved surfaces arresting substantial fore and aft movement of said transfer conveyor with respect to said locomotive as relative fore and aft movement between the locomotive and tender occurs.

2. In combination with an intercoupled locomotive and tender, the former having a boiler backwall and a frame, and the latter being provided with a fuel bin, a fuel transfer conveyor leading forwardly from said tender to said locomotive comprising a trough portion underlying said bin and a conduit portion rigid with said trough portion, the forward end of said conduit portion being disposed above the level of said trough portion, means carried by said trough portion movably supporting said transfer conveyor on the tender, means carried by the boiler backwall arranged to flexibly support the forward end of said conduit portion, said fuel transfer conveyor being provided with a depending foot member, and a support member carried solely by the frame of the locomotive, said members being disposed intermediate said first and second named means, one of said members at its free end having a concave surface and the other of said members at its free end having a convex surface, one of said curved surfaces fitting into the other of said curved surfaces, the engagement of said curved surfaces arresting substantial fore and aft movement of said transfer conveyor with respect to said locomotive as relative fore and aft movement between the locomotive and tender occurs.

CHARLES J. SURDY.
